UNITED STATES PATENT OFFICE.

CLARENCE ARTHUR KNOWELDEN, OF LEWISHAM, ENGLAND, ASSIGNOR TO THE REINFORCED BRICKWORK COMPANY, LIMITED, OF WINNIPEG, CANADA, A CORPORATION OF MANITOBA, CANADA.

WIRE-NETTING MACHINE.

1,119,759.

Specification of Letters Patent. Patented Dec. 1, 1914.

Application filed December 2, 1913. Serial No. 804,183.

To all whom it may concern:

Be it known that I, CLARENCE ARTHUR KNOWELDEN, a British subject, residing at Lewisham, in the county of Kent, England, 5 have invented certain new and useful Improvements in Wire-Netting Machines; and I hereby declare that the following is a full, clear, and exact description of the same.

My invention relates to a wire netting machine comprising twisting and driving elements so arranged that the mesh wires will be twisted around longitudinally arranged strand wires, and one of the objects of my invention is to so construct the machine that 15 the strand wires will pass axially through the driving elements and be prevented thereby from being entangled with the twisting mechanism.

A further object of my invention is to 20 so construct the driving and twisting elements that they will converge in the direction of the mesh roller, this convergence creating a tapering formation of the driving elements, which permits of the employment 25 of conical shaped cop tubes with increased cop holding capacity without a corresponding increase in the width of the wire netting, the cop tubes extending through the twisting mechanism to permit of the wire cops 30 being readily placed therein without the necessity of removing said cop tubes from the machine.

In carrying out these objects I have made the driving elements of a tapering shape, 35 and have formed through each of the driving elements an axial bore extending from one end to the other, and have mounted these driving elements in suitable bearings, which are so constructed as to resist the end 40 thrust of the driving elements and their related parts, and I have provided the driving elements with trunnions on which are slidably keyed clutch members to engage with the clutch members of the driving pinions 45 loosely mounted upon the trunnions and meshing with a rack by which motion is transmitted to the driving elements when the clutch elements are engaged, and I have so arranged these clutch elements that when 50 the rack is moving in one direction it will transmit motion to alternate driving elements, and cause their rotation, and will on the return motion of the rack cause the rotation of the remaining driving elements.

I have provided the twisting elements 55 with conical-shaped cop tubes located in the intervals between each adjacent pair of driving elements, and I have extended the bores of the cop tubes through the twisting elements so that the wire cops can be introduced into the cop tubes without necessitating their removal from the machine.

For an understanding of the invention reference is to be had to the following description, and to the accompanying drawings in which:

Figure 1 is a plan view of the wire netting machine. Fig. 2 is a front elevation of the machine, Fig. 3 is a rear elevation, Fig. 4 is a broken sectional view showing the 70 bearings for the driving and twisting elements, Fig. 5 is a sectional view through the driving and twisting elements, on the line a—a, Fig. 4, Fig. 6 is an elevation of the bearings for the driving and twisting 75 elements shown in Fig. 5, Fig. 7 is a perspective view of one of the driving elements, Fig. 8 is a perspective view of one of the twisting elements, Fig. 9 is a detail view of the levers for moving the clutch members of the driving elements, and Fig. 10 is a broken view of the wire netting.

Like characters of reference refer to like parts throughout the specification and drawings.

On the top of the frame a near the front thereof is a slide way b for the rack c, and meshing with the rack c are a set of pinions d, d', d'' and d³. These pinions are loosely mounted upon the trunnions e of the driving elements f, f', f'', and f³ respectively, the trunnions being journaled in bearings g in the gear box h. The gear box h is fastened to the frame a above the slide way b, and the trunnions project through the bearings 95 g to the front of the gear box.

The pinions d, d'' are each provided, preferably with a ratchet faced clutch member i, and the pinions d', d³ are each provided preferably with a ratchet faced clutch member i', the inclined surfaces of the clutch members i being reversed with respect to the inclined surfaces of the clutch members i'.

Slidably keyed to the trunnion e, are 105 clutch members j, j', j'' and j³ respectively, the clutch members j and j'' engaging with the clutch members i of the pinions d and d''.

respectively, and the clutch members j' and j^3 engaging with the clutch members i' of the pinions d' and d^3 respectively.

Each of the clutch members j, j', j'' and j^3 is formed with a circumferential groove k , and engaging in the grooves k , are the pins l, l', l'' and l^3 of the levers m, m' . The levers m and m' are fulcrumed at m'' and are coupled together by a link o , so that they will act simultaneously when operating to move the clutch members of the driving elements into engagement with the clutch members of the pinions.

When the rack c is moving in the direction indicated by arrow in Fig. 1, it meshes with and rotates all of the pinions $d, d', d'',$ and d^3 . The motion of the pinions $d, d'',$ is transmitted to the driving elements f, f'' by the clutch members i of the pinions d, d'' engaging with the clutch members j, j'' of said driving elements. The faces of the clutch members i' of the pinions d', d^3 being oppositely inclined to those of the clutch members i of the pinions $d, d'',$ will throw the clutch members j, j'' out of engagement until the rack c has moved to its limit of motion in the direction indicated by arrow shown in Fig. 1, and has started its return. When the rack has reached its limit in this direction, its motion is reversed, and this reversal of motion causes the reverse revolution of the pinions d, d', d'' and d^3 .

When the motion of the pinions is reversed, as indicated by arrow in Fig. 4, the inclined faces of the clutch members i of the pinions d, d'' move the clutch members j, j'' out of engagement, and as the clutch members j, j'' disengage from the clutch members i they rock the levers m, m' on their fulcrums m'' and cause the pins l', l^3 to throw the clutch members j', j^3 into engagement with the clutch members i' of the driving elements f', f^3 to revolve the said driving elements f', f^3 , until the rack has reached its limit of movement in the reverse direction, and has started to move again in the direction indicated by arrow in Fig. 1, when the clutch members j', j^3 are disengaged from the clutch members i' , and the clutch members j, j'' are reengaged with the clutch members i . By means of this movement the alternate driving elements are rotated when the rack is moving in one direction, and the remaining driving elements are rotated when the rack is moving in the opposite direction.

Each of the driving elements f, f', f'' and f^3 consists of two tapering journals p, p' rigidly connected by a bar q . Each of the tapering journals p, p' of the driving elements f, f'' is formed with curved or lune-shaped recesses r on opposite sides of the vertical axis of the driving element as shown in Fig. 7, and each of the tapering journals of the driving elements f, f^3 is formed with

a curved recess r on one side only of the vertical axis of those driving elements, and contained in the curved recesses r are the lunes s, s', s'' of the twisting elements, the cop tubes t of which extend through said lunes and are preferably tapered to correspond with the taper of the driving elements. 70

Each of the driving elements is formed with an axial bore u through which a strand 75 wire v passes from the bobbin u' to the mesh roller w , the bore u extending through the trunnion, tapering journals, and connecting bar of its respective driver. The advantage of this construction is that should the strand wire 80 break it will be prevented from becoming entangled in any of the rotating parts of the twisting mechanism. Contained in the cop tubes t are wire cops x leading to the mesh roller w to form the mesh wires y of the wire 85 netting when the strand and mesh wires are netted together. The strand wires v and the wires from the wire cops x pass over the mesh roller w , and when the rack c commences its movement in the direction indicated by arrow in Fig. 1, it revolves the driving elements f, f'' and these driving elements as they rotate carry with them all of the twisting elements, each driving element causing the lune or lunes carried by it to 90 revolve around its respective axis. On the reverse movement of the rack c the driving elements f, f'' remain stationary, and the driving elements f', f^3 are caused to revolve and carry with them all of the twisting elements in the reverse direction of revolution to that previously described. As the twisting elements revolve with the driving elements they twist the mesh wires y around the strand wires v and form the meshes 100 105 which bind the strand wires together for the wire netting, the wire netting being taken from the mesh roller w and wound on the winding roller z .

As shown in Fig. 1, the tapering journals 110 p of the driving elements f, f', f'' and f^3 are mounted in bearings a' on the frame a adjacent to the gear box h , and the journals p' are mounted in bearings a'' on the frame a in rear of the bearings a' . The bearings 115 a' and a'' are tapered to correspond with the taper of the journals p, p' so that the driving and twisting elements may taper evenly from the bearings a' toward the bearings a'' , and if projected beyond the bearings a'' converge at the point b' indicated on Fig. 1 of the drawings. This point b' may be said to be the point from which the axis of the driving and twisting elements radiate, this radiation having the effect of 120 125 producing tapering intervals between the connecting bars q and the tapering cop tubes t .

The advantage of this construction is that the width of the twisting and driving ele- 130

ments at the rear end of the machine, where the netting is formed, corresponds to the width of the netting, and that the width of the front end of the twisting and driving elements is relatively greater than the rear end, to permit of tapering cop tubes being employed to contain conical shaped cops of wire for forming the meshes. By making these cop tubes of a conical shape it is possible to increase their wire holding capacity without increasing the width of the wire netting.

The tapering formation of the driving and twisting elements in addition to permitting of an increased holding capacity of the cop tubes, also has the advantage of creating a relatively tight fit of the journals in their bearings as the bearings are tapered to correspond with the taper of the journals, and owing to the action of the mesh roller in drawing the wires through the cop tubes, a strain is imposed on these parts and on the driving elements rearward of the machine, which has the effect of causing the tapering journals to continually bear toward the smaller end of the bearings. To resist the end thrust of the driving and twisting elements the bearings a'' are provided with thrust shoulders a^3 which engage the adjacent side faces of the tapering journals and lunes and thus prevent them binding in their bearings, see Fig. 4.

The rack c is moved back and forth by means of a lever c' fulcrumed to the frame of the machine and actuated by a disk and pin c'' rotated by a shaft g' revolved by bevel gear wheels g'' driven by the shaft g^3 .

The mesh roller w is driven from the shaft g^3 by an eccentric motion h' , and the winding roller z is driven from the mesh roller w by a belt and pulley drive w'' .

The above described motions for the rack, mesh roller, and winding roller may be varied within the scope of the appended claims without departing from the principle of the invention.

Having now fully described and ascertained the nature of my said invention, and in what manner the same is to be performed, I declare that what I claim is:—

1. In a wire netting machine, a set of twisting elements, each comprising a tapering tube for a wire cop and lune-shaped members near the ends of said tube, in combination with a set of driving elements each comprising two tapering journals, with lune-shaped recesses in their peripheries to receive the lune-shaped members of the cop tubes, and a connecting member for said journals, said journals and connecting members being axially bored for the feed of the strand wires, and means for causing the revolution of the alternate driving elements and all the twisting elements.

2. In a wire netting machine, a set of twisting elements, each comprising a tapering tube for a wire cop and lune-shaped members near the ends of said tube, in combination with a set of driving elements each comprising two tapering journals, with lune-shaped recesses in their peripheries to receive the lune-shaped members for the cop tubes, and a connecting member for said journals, said journals and connecting members being axially bored for the feed of the strand wires, and means for causing the revolution of the alternate driving elements and all the twisting elements.

3. In a wire netting machine, a set of twisting elements, each comprising a tapering tube for a wire cop and lune-shaped members near the ends of said tube, in combination with a set of driving elements each comprising two tapering journals, with lune-shaped recesses in their peripheries to receive the lune-shaped members for the cop tubes, and a connecting member for said journals, said journals and connecting members being axially bored for the feed of the strand wires, and means for causing the revolution of the alternate driving elements and all the twisting elements, said means comprising trunnions projecting beyond the journals at one end of the driving elements, pinions with clutch members loosely mounted on said trunnions, clutch members slidably keyed on said trunnions and engaging those of said pinions, and a rack meshing with said pinions to cause their revolution.

4. In a wire netting machine, a set of twisting elements, each comprising a tapering tube for a wire cop and lune-shaped members near the ends of said tube, in combination with a set of driving elements, each comprising two tapering journals, with lune-shaped recesses in their peripheries to receive the lune-shaped members for the cop tubes, and a connecting member for said journals, said journals and connecting members being axially bored for the feed of the strand wires, and means for causing the revolution of the alternate driving elements and all the twisting elements, said means comprising trunnions projecting beyond the journals at one end of the driving elements, pinions with clutch members loosely mounted on said trunnions, clutch members slidably keyed on said trunnions and engaging those of said pinions, and a rack meshing with said pinions to cause their revolution.

5. In a wire netting machine, a set of twisting elements each comprising a tapering tube for a wire cop and lune-shaped members near the ends of said tube, in combination with a set of driving elements,

6. In a wire netting machine, a set of twisting elements, each comprising a tapering tube for a wire cop and lune-shaped

each comprising two tapering journals, with lune-shaped recesses in their peripheries to receive the lune-shaped members for the cop tubes, and a connecting member for said journals, said journals and connecting members being axially bored for the feed of the strand wires, means for causing the revolution of the alternate driving elements and all the twisting elements, said means comprising trunnions projecting beyond the journals at one end of the driving elements, pinions with clutch members loosely mounted on said trunnions, clutch members slidably keyed on said trunnions and engaging those of said pinions, and a rack meshing with said pinions to cause their revolution, the clutch members of the alternate driving

elements being oppositely disposed, whereby one half the number of driving elements will be revolved as the rack moves in one direction, and the other half will be revolved as the rack moves in the opposite direction, and means actuated by the clutch members of the alternate driving elements for moving the clutch members of the remaining driving elements into engagement at each reversal of the movement of said rack. 20 25

Toronto, November 3rd 1913.

CLARENCE ARTHUR KNOWELDEN.
